[57] CLAIM

The ornamental design for an adjustable table, substantially as shown and described.

DESCRIPTION

FIG. 1 is a perspective view of an adjustable table embodying this invention with its top in a partially raised and inclined position.

FIG. 2 is an elevational front view of the table of FIG. 1.

FIG. 3 is an elevational view of the left-hand side of the table of FIG. 1 as referenced by an observer located in front of and viewing the front of the table.

FIG. 4 is an elevational view of the right-hand side of the table of FIG. 1 as referenced by an observer located in front of and viewing the front of the table.

FIG. 5 is a top view of the adjustable table of FIG. 1.

FIG. 6 is an elevational back view of the table of FIG. 1.

FIG. 7 is a bottom view of the table of FIG. 1.
